UNITED STATES PATENT OFFICE.

CHARLES S. WHISTON, OF PITTSBURG, PENNSYLVANIA.

REIN-HOLDER.

SPECIFICATION forming part of Letters Patent No. 357,946, dated February 15, 1887.

Application filed July 3, 1886. Serial No. 207,116. (No model.)

To all whom it may concern:

Be it known that I, CHARLES SHALER WHISTON, of Pittsburg, in the county of Allegheny and State of Pennsylvania, have invented 5 certain new and useful Improvements in Rein-Holders; and I do hereby declare the following to be a full, clear, and exact description of the invention, such as will enable others skilled in the art to which it pertains to make and 10 use the same.

My invention relates to rein-holders, the object being to provide a device of this character of simple, economical, and durable construction adapted to be readily attached to the 15 edge of a vehicle dash-board.

The invention consists in the combination, with a stationary lower jaw, of a spring-pressed upper jaw adapted to yield at each end.

The invention further consists in the various features of construction, hereinafter fully described, and pointed out in the claims.

In the accompanying drawings, Figure 1 represents my improved rein-holder applied to a dash-board. Figs. 2, 3, 4, and 5 illustrate parts in detail.

The lower jaw, A, of the device is grooved on its undersidethroughout its length to adapt it to fit snugly upon the rounded edge of a dash-board, and said jaw is beveled at the upper sides of its ends, as seen at *a a*.

B represents a lug or plate formed integral with the jaw A at one side of the latter, and said lug is inwardly curved at its lower end, *b*.

C represents a removable lug or plate corresponding in form to the lug B, secured removably to the jaw A, opposite the lug B, by screws *c*, the said jaw being recessed to receive the lug.

D represents a yielding jaw arranged upon the jaw A, and grooved on its under side, as shown at *d*, and centrally recessed on its under side to fit over a central upward projection, *e*, formed upon the jaw A. The ends of the jaw B are bent upwardly to form, in connection with the beveled ends of the jaw A, flaring spaces *E E*, to receive the reins. The jaw D is held in place by means of a screw, F, which passes through an opening, *f*, in said

jaw and into a threaded socket, *f'*, formed in the central projection, *e*, of the lower jaw. 50 Between the upper side of the jaw D and the head of the screw F is interposed a spanning spring, G, whose ends are held in depressions *h h*, formed in the upper surface of the jaw D, and whose central portion is provided with an 55 opening, *i*, through which the screw passes.

The device as thus constructed is adapted to be removably secured to the edge of a dash-board by clamping the latter between the curved lugs B and C, the lug C, as already explained, being removable to permit of the attachment.

The reins are adapted to be slipped between the jaws, one rein at each end, through the spaces *E E*. It will be apparent that the jaw 65 D will readily yield at each end to receive the reins, and the grooving of the under surface of said jaw forms biting-edges *l* to securely retain the reins.

I do not limit myself to the precise construction here shown and described, but reserve the right to make all such alterations and modifications as may properly fall within the scope of my invention.

Having fully described my invention, what I 75 claim, and desire to secure by Letters Patent, is—

1. In a rein-holder, the combination, with a lower stationary jaw, of an upper yielding jaw provided with a spanning spring and a 80 screw, which latter passes loosely through an opening in the jaw, substantially as described.

2. A rein-holder consisting of a lower jaw adapted to be clamped to a dash-board and provided with a central upward projection, 85 and an upper jaw recessed to fit said projection, a clamping-spring, and a securing-screw, substantially as described.

In testimony whereof I have signed this specification in the presence of two subscribing witnesses.

CHARLES S. WHISTON.
